(57) **CLAIM**

The ornamental design for a large pet food storage container, as shown and described.

DESCRIPTION

FIG. 1 is a perspective view of a large pet food storage container embodying my design, with the feet and lower margin of the basin, the hinge assembly for the primary lid, the latch assemblies for releasably securing the primary lid in the closed position, a number of sections along the primary lid, the auxiliary lid, the hinge assembly for the auxiliary lid, the recessed portion of the front wall for receiving the auxiliary lid of a lower stacked container (not shown), and the corrugations spaced about the sidewall of the basin being shown in broken lines for illustrative purposes only and forming no part of the claimed design;

FIG. 2 is a front elevation view of the large pet food storage container shown in FIG. 1;

FIG. 3 is a side elevation view of the large pet food storage container depicted in FIGS. 1 and 2, with the opposite side elevation being a mirror image thereof;

FIG. 4 is a rear elevation view of the large pet food storage container depicted in FIGS. 1-3;

FIG. 5 is a plan view of the large pet food storage container depicted in FIGS. 1-4; and,

FIG. 6 is a bottom elevation view of the large pet food storage container depicted in FIGS. 1-5.
